UNITED STATES PATENT OFFICE

2,206,240

GAME

Hans Skreberg, Big Bend Township,
Chippewa County, Minn.

Application October 6, 1938, Serial No. 233,593

1 Claim. (Cl. 124—4)

This invention relates to games, and more particularly to an amusement device forming a catapult and projector for rolling and ejecting a playing disc.

5 The object of my present invention is to provide a catapult or projector adapted to be placed on a floor or other horizontal surface that will enable a person playing the game to make a disc roll, jump, and also perform in other ways.

10 My present improvement in games may be made from wood, metal, or combinations of suitable materials, and the size may be varied without departing from the object or scope of the invention.

15 The novel features of construction, and combination and arrangement of parts, is fully illustrated in the accompanying drawing and defined in the appended claim.

Fig. 1 is a side elevation showing a playing disc 20 in position on the rocking arm of the projector.

Fig. 2 is a side elevation showing how a playing disc is rolled off the rocking arm of the projector when the arm is depressed by a stroke from a playing stick.

25 Fig. 3 shows the opposite side of the projector as compared with Fig. 1.

Fig. 4 is a side elevation showing a playing disc hung on the top face of the upwardly extending curved section of the rocking arm of the projector, and how the playing disc is ejected off the rocking arm by a stroke at opposite end of arm by a playing stick.

30 Fig. 5 shows how anvil-forming end of rocking arm serves as a rest for a playing disc when the said disc is projected by inserting a playing stick in a hole in the disc.

Fig. 6 is an end view of the projector showing the anvil-forming section of rocking arm and its relation with a playing stick.

40 Similar reference characters designate corresponding parts throughout the several figures and drawing.

As will be observed from the drawing, the base A forms the support for the semi-circular member B, and also for a member C.

Members B and C extend upward from base A and form the bearings for the rocking arm D.

45 Members B and C also form guides for a playing disc E, when said disc is in position on concave section M of the rocking arm D, as shown in Fig. 1.

The playing disc guide sections of members B and C are designated as N and O, in Fig. 4.

The end of rocking arm D where a playing disc to be projected is hung is designated as J, and the opposite end of the rocking arm D which forms a striking anvil for a playing stick F is designated in the several figures as K.

Playing stick is designated as F in Fig. 5.

The top faces of rocking arm D are parallel with bottom face of same, and bottom face of 10 rocking arm rests on the base A when said arm is in its normal position.

The semi-circular member B, which is connected with member C by means of the rocking arm pivot bolt H, forms a guide for the rocking 15 arm D during its entire movement from normal to depressed position, eliminating side-sway and weaving of said arm.

In Fig. 6 hole in member B for rocking arm pivot bolt H is designated as G, and hole for 20 same bolt in rocking arm D as I.

Characters L, in Fig. 1, Fig. 3, and Fig. 6, represent rivets connecting member C with base A.

Without further description it is thought that the features and advantages of the invention 25 herein shown and described will be readily apparent to those skilled in the art as an amusement device providing safe and wholesome fun and healthful exercise for children and adults, both as an indoor and outdoor sport, and very inexpensive to manufacture.

I claim:

A projector for an annular playing disc comprising, in combination, a base, two upwardly extending supporting members secured thereon, 35 said members having their adjacent faces parallel and spaced apart, a throwing lever pivoted intermediate its ends between said members, said lever having one arm with a flat portion on the lower surface upon which the arm normally rests 40 and a concave upper surface complementary to the edge of the disc to be projected, said upwardly extending supporting members acting as guides to hold the disc in the concave portion of the arm when said arm is in normal position, said lever 45 having its opposite arm upwardly inclined when in normal position and terminating in a normally horizontal surface such that when said arm is struck with a playing stick or other means the disc will be projected.

50

HANS SKREBERG.
